OF SYRACUSE, NEW YORK.

TYPE-WRITING MACHINE.

No. 895,912.

Specification of Letters Patent.

Patented Aug. 11, 1908.

Application filed February 7, 1907. Serial No. 356,242.

To all whom it may concern:

Be it known that I, CHARLES E. TOMLINSON, a citizen of the United States, and resident of Syracuse, in the county of Onondaga and State of New York, have invented certain new and useful Improvements in Type-Writing Machines, of which the following is a specification.

My invention relates to typewriting machines and more particularly to ribbon mechanism, and while the invention from certain aspects involves broadly new features, yet it is shown applied to ribbon mechanism generally resembling, and from 15 certain aspects it is in the nature of an improvement on the construction set forth in the application of Alexander T. Brown, Serial No. 305,561, filed March 12th, 1906.

It is desirable when employing ribbon vibrating mechanism that the ribbon when in the normal position be maintained as close as possible to the printing point or line without, of course, obstructing the operator's view of the written matter. This is to provide as short a throw of the ribbon as possible to bring it to the printing point in order that the ribbon vibrating mechanism shall add as little as possible to the resistance on the keys, so that the "touch" may not be impaired by said vibrator. In some machines heretofore devised, in which means were provided for doing mimeograph work, the ribbon is maintained quiescent in the normal position during the preparation of 30 mimeograph sheets, and if the ribbon in its normal position is maintained close to the printing point or line there is liability of the stem letters or characters which extend below the base line, such as the *y*, *j*, *ƒ*, *%*, 40 and *\$*, accidentally causing an imprint through the ribbon on a mimeograph sheet when none is intended. If, on the other hand, the ribbon in its normal position is located at a sufficient distance from the printing point to prevent the accidental imprint described above, then an additional throw must be given the ribbon in order to bring it to the printing point.

One of the objects of my present invention 50 is to overcome these difficulties and to provide simple and efficient ribbon vibrating mechanism which does not add appreciably to the touch of the machine and in which when mimeograph sheets are being written

on the machine there is no liability of the types striking the ribbon.

A further object of my invention is to provide in a ribbon mechanism of the character specified, means whereby either one of a plurality of fields of different characteristics of 60 the ribbon may be employed at will.

A still further object of my invention is to provide simple and efficient ribbon mechanism in which the ribbon vibrator may be so actuated at each operation of a type action 65 that it will not be interposed in the path of the approaching type so that mimeograph sheets may be readily produced on the machine when desired.

To the above and other ends which will 70 hereinafter appear, my invention consists in the features of construction, arrangements of parts and combinations of devices to be set forth in the following specification and particularly pointed out in the appended claims. 75

In the drawings, Figure 1 is a fragmentary central vertical sectional view of one form of typewriting machine with the features of my invention applied thereto, sufficient of the machine being shown to illustrate my invention. Fig. 2 is a detail front elevation of some of the parts, the ribbon being shown in the normal position. Fig. 3 is a detail fragmentary perspective view showing parts of the ribbon vibrator actuating mechanism. 85 Figs. 4, 5 and 6 are detail side elevations of the ribbon vibrator and its controlling and actuating means, the different views illustrating different positions of the parts under different adjustments. 90

The side plates 1 of the machine are formed with posts 2 which support a top plate 3. Segmentally arranged upwardly and rearwardly striking type bars 4 are supported on ball bearings and impact against the front 95 face of the platen 5 diagrammatically shown in Fig. 1. The platen is supported by a carriage (not shown) which travels over the top plate from side to side of the machine. Each type bar is pivotally connected at 6 to a link 7 100 pivoted at its lower end to an actuating or sub-lever 8 pivoted on a segmental pivot wire 9 and working in a slot in a segmental support. The lower end of each lever 8 is provided with a hook-like portion 10 coöperative with one end of a restoring spring 11 105 which is secured at its opposite end to a hook 12. Each sub-lever 8 has a forwardly ex-

tending link 13 pivoted thereto, the forward end of each link being pivotally connected to a bell crank lever 14 pivoted on a rod 15 and connected by a pivot 16 with a key stem 5 17 having a finger piece or button 18. As shown in Fig. 1 the forward ends of the type bars are supported in their normal positions on a segmental type rest or pad 19. A depression of a printing key 18 actuates the 10 associated bell crank 14 and causes the upper end of the associated sub-lever 8 to be moved forwardly, thereby swinging its type bar up to the printing position. The type action just described is not of my invention, but is 15 the invention of John H. Barr.

Situated below and in the rear of the hook-like members 10 is a segmental universal bar 20 angular in cross section and with which each of said members 10 coöperates or 20 contacts when the associated type bar has moved about one-half the length of its travel to the printing point, as shown in Fig. 1. Up to this time the different portions of the type action move independently of the universal 25 bar and the resistance due to moving the universal bar and the parts controlled thereby does not operate against the type action, so that the parts of the type action have acquired momentum and the type bar has 30 completed about one-half of its stroke when the resistance of the universal bar and the parts controlled thereby is brought into play, and at this time the said resistance does not become appreciable so that an easy touch 35 40 may be provided at the first portion of the key stroke and until the type bar has traveled about one-half the extent of its movement. The universal bar is provided with rearwardly extending ears 21 each apertured 45 to receive a pivot by which the universal bar is connected to the parts by which it is supported. These parts comprise upwardly extending arms 22 which project from a rock shaft 23 mounted in bearings in the side 50 plates 1, each of the arms 22 being situated near one of the side plates. A centrally located upwardly projecting arm 24 extends from a rock shaft or frame 25 pivoted at its 55 ends on bearing screws 25^a (Fig. 3) which are received in threaded openings in the side plates 1 of the frame. The arms 22 and 24 constitute in effect parallel links on which the universal bar is mounted and guided. A rearwardly extending crank arm 26 projects 60 from the rock shaft 23 at one side of the machine and is pivotally connected at its rear end to a depending link 27, the lower end of which is pivoted at 28 to a rearwardly projecting crank arm 29 on the rock shaft or 65 frame 25. Thus the two rock shafts 23 and 25 are connected together so that a rearward movement of the universal bar 20 imparted by contact therewith of a sub-lever 8 effects a rocking movement of the arms 22 and 24 70 to turn the rock shafts 23 and 25 in their

bearings and so that all parts of said universal bar move in unison, every point of said universal bar moving to the same extent as and parallel to every other point thereof.

From an inspection of Fig. 3 it will be seen 70 that the rock shaft 25 is provided with a yoke-like projection 29^a which in part is formed by the arm 29 and that an arm or bar 30 is secured at one end by a nut 31 to a cross bar 32 of the yoke. The arm or bar 30 75 thus extends through the pivotal axis of the frame or rock shaft 25 and to opposite sides thereof. A block 33 is mounted on the arm 30 and is adapted to be adjusted along said arm to different distances from the pivotal 80 center of the rock shaft or frame 25 and to opposite sides of said pivotal center. The adjustment of the block 33 from one end portion of the rod 30 to the opposite end portion from that where it is shown in Fig. 3 brings 85 the block within the yoke 29^a. A bifurcated member 34 is pivoted at 35 to the block 33, this bifurcated member being riveted or otherwise connected as at 36 to an upwardly extending link 37. The upper end of the 90 link 37 is pivoted at 38 to a crank arm 39 projecting rearwardly from a rock shaft 40 which extends across the machine from side to side thereof and is mounted to turn in bearings carried by the top plate. The link 95 37 and crank arm 39 are situated adjacent to one of the side plates 1 of the machine, whereas a forwardly extending crank arm 41 is secured to the rock shaft and projects 100 therefrom about centrally of the machine. 105 This last mentioned crank arm is pivotally connected at 42 with a ribbon vibrator 43 guided at the upper portion thereof in a fixed guide or bracket 44. From an inspection of Fig. 1 it will be seen that the arm or bar 30 is 110 formed as an arc of which the pivot 38 of the link 37 is the center, so that an adjustment of the lower end of the link with the block 33 along said arm 30 does not effect a change in the upper end of the link and the vibrator remains in the same normal position in all of the adjusted positions of the link shown in the full and dotted lines in Fig. 1. The ribbon vibrator may be of any suitable construction and is slotted to form a guide for a ribbon A which may be divided into fields of different characteristics. The ribbon shown in the present instance is divided into two fields a and b of different colors such as black and red respectively, or one of the fields may be 115 impregnated with copying ink and the other with record ink. The ribbon passes through the guide in its movement from one ribbon spool to another, the ribbon spools and ribbon feed mechanism not being shown in the 120 present instance, though they may be of a character such as those shown in the application of A. T. Brown hereinbefore referred to or of any other suitable construction.

In order to adjust the block 33 to different 130

points along the bar 30, a forwardly extending link 45 is pivoted at its rear end to the lower end of the link 37 and to the adjustable block 33, whereas the forward end of said link is pivoted at 46 to a lever 47 pivoted at 48 to the left-hand side plate 1 of the machine. A key stem 49 is pivoted at 50 to the lever 47 on one side of the pivot 48 thereof, whereas another key stem 51 is pivoted to said lever at 52 on the opposite side of its pivot 48. The key stem 49 is provided with a finger piece or button 53 and the key stem 51 is provided with a button or finger piece 54. An angular nose or projection 55 is formed on the lever 47 for co-operation with an anti-friction roller 56 carried by a lever 57 pivoted to the left-hand side plate 1 of the machine on a headed pivot screw 58. The rear end of the lever 57 is connected to one end of a contractile spring 59, the other end of said spring being connected to a pin 60 which projects from the left-hand side plate. Said pin 60 also serves as a stop to limit the motion of the lever arm 47 toward the rear of the machine. The motion of said lever arm in the opposite direction is limited by a stop 61 secured to a spindle 62 which receives a bearing in the left-hand side plate and extends therethrough to the outside of the frame of the machine where it is provided with a button or finger piece 63 by which the stop 61 may be turned or adjusted around its pivotal center to either of the positions shown in full and dotted lines in Fig. 1.

35 The block 33 and the lower end of the link 37 are shown in Figs. 1 and 5 adjusted rearwardly to the greatest distance from the pivotal center of the frame or rock shaft 25, so that the greatest extent of throw is imparted 40 to the ribbon vibrator by an operation of a type action at this time to bring the lowermost or red field *b* of the ribbon to the printing point indicated by the line *c* in Fig. 5. When the finger key 53 is depressed it forces the lever 47 around its pivot 48 until it is brought into contact with the end of the stop 61. The effect of this movement is to cam the lever 57 upwardly against the tension of the spring 59 until the apex of the projection 55 passes the 45 center of the roller 56. Then pressure of the spring 59 will be exerted to maintain the lever 47 in its shifted position against the end of the stop 61. The effect of this movement of the key 53 is to move the block 33 forwardly to the intermediate dotted line position shown in Fig. 1, which is the position also shown in Fig. 4, thereby bringing the lower end of the link nearer to the pivotal center of the frame or rock shaft 25. The 50 effect of this adjustment is to decrease the extent of throw imparted to the ribbon vibrator so that an actuation of a printing key at this time will cause the ribbon to be moved to the position shown in Fig. 4 so that the 55 uppermost or black field *a* of the ribbon will

be carried to the printing point and interposed in the path of the approaching type.

From an inspection of Figs. 1 and 2 it will be understood that in the normal positions of the parts the upper edge of the ribbon is maintained close to the printing point *c* and close to what may be termed the base line of the letters indicated by a dotted line *d* in Fig. 2. If the vibrator remained quiescent in the position indicated when mimeograph sheets are being produced those letters or characters which extend below the base line *d* would contact with the ribbon and produce an imprint of a portion of each such letter or character on the mimeograph sheet. I have therefore provided means for moving the ribbon away from the printing point or line at each actuation of a type bar when mimeograph sheets are being prepared on the machine. Thus by moving the stop 61 to the dotted line position in Fig. 1 the tension of the spring 59 is exerted to move the lever 47 to the foremost position shown in dotted lines in said figure and against a side of the stop 61. The effect of this movement is to adjust the block 33 and the lower end of the link to the opposite side of the pivotal center of the rock shaft or frame 25 from that shown in full lines in Fig. 1 and as indicated in Fig. 6 and in dotted lines in Fig. 1. When the parts are set to write on either the red or black field of the ribbon an actuation of a type bar effects a rearward movement of the universal bar, thus rocking the shaft 25 to effect a downward movement of the rear end 100 of the arm 30. This movement transmits a downward movement to the link 37, as indicated by the arrows *e* and *f* (Fig. 1) and moves the ribbon upwardly to the printing point as heretofore explained. When, however, the parts are set for mimeograph work and the lower end of the link is adjusted to the opposite side of the pivotal center of the rock shaft or frame 25 the upward movement of the forward end of the bar 30 will 105 transmit an upward movement to the link 37, or in the direction of the arrow *g* in Fig. 1, so that the ribbon vibrator at this time will receive a downward movement to carry the ribbon away from the printing point instead of an upward movement to carry the ribbon to the printing point. 110

From the foregoing description it will be understood that the adjustment of the lower end of the link 37 with the block 33 to different distances from the pivotal center of the rock shaft or frame 25 determines the extent of throw of the ribbon vibrator from a fixed normal position close to the printing point or line in order to bring either of the fields *a* or *b* into operation as may be desired, and that the adjustment of the lower end of the link with the block 33 to the opposite side of the pivotal center of the frame 25 changes 115 the direction of the movements of the link 120

125 130

37. The rock shaft 40 and the parts connected thereto thus move the ribbon down away from the printing point instead of in an opposite direction where it would be interposed in the path of the approaching type. It will also be seen that the universal bar and the ribbon mechanism controlled thereby are taken up at the same point in the key depression irrespective of the adjustment of the 10 parts whether the ribbon field *a* or *b* is in operation or the machine is being employed for writing mimeograph sheets; so that the resistance offered to the keys by an actuation of the ribbon mechanism is substantially uniform 15 under different conditions and this resistance is not offered to the type action until a momentum of the parts has been acquired and the type bar has completed about one-half of the stroke so that an easy touch is 20 provided under all conditions.

While I have shown one means of carrying out my invention it should be understood that the invention may be applied to various styles of typewriting machines, and that various changes may be made without departing 25 from my invention.

Certain of the features shown in the accompanying drawings form no part of my present invention. The construction of the top plate 30 of the machine forming a dust guard over the bearings of the type bars is not of my invention, but is the invention of A. J. Briggs. Certain features of the ribbon controlling mechanism herein shown are not of my invention 35 but are the invention of Alexander T. Brown and are claimed in his application, Serial No. 305,561 heretofore referred to.

What I claim as new and desire to secure by Letters Patent, is:—

40 1. In a typewriting machine, the combination of means for automatically moving a ribbon to the printing point at each depression of a printing key, and regulating means co-operative with said ribbon moving means 45 to cause the latter to effect a movement of the ribbon away from instead of to the printing point at each depression of a printing key.

50 2. In a typewriting machine, the combination of a ribbon normally away from the printing point, and means for automatically moving said ribbon at will in either of two opposite directions from the normal position at each approach of a type to the printing 55 position, the movement of the ribbon in one direction being to the printing point and the movement of the ribbon in the other direction being away from the printing point.

60 3. In a typewriting machine, the combination of a ribbon normally away from the printing point, type bars, means for moving said ribbon in either of two opposite directions from the normal position at each approach of a type bar to the printing position

and means operable at will for controlling 65 the direction of movement of the ribbon, whereby the ribbon will be moved from the normal position to the printing point when said controlling means is in one position and the ribbon will be moved from the normal position away from the printing point when the controlling means is in another position. 70

4. In a typewriting machine, the combination of an automatically actuated ribbon vibrator, and adjustable means for controlling 75 the direction of movement of the ribbon vibrator from the normal position, the movement of the vibrator from the normal position being in one direction under one adjustment of said adjustable means and in another 80 direction from the normal position under another adjustment of said adjustable means.

5. In a typewriting machine, the combination of a ribbon vibrator, and means for moving and for changing the direction of movement 85 of the vibrator from the normal position.

6. In a typewriting machine, the combination of a ribbon normally away from the printing point, means for automatically moving 90 said ribbon at each printing operation, and means regulatable at will to change the direction of movement transmitted by said moving means.

7. In a typewriting machine, the combination of a ribbon normally away from the printing point, means for automatically moving 95 said ribbon at each printing operation, said means including a pivoted device, and means for shifting at will the connection with 100 said pivoted device to either side of the pivotal center of said device.

8. In a typewriting machine, the combination of a ribbon vibrator, a universal bar, and intermediate connections between said 105 universal bar and said vibrator, said connections including means capable of such adjustment as will change the direction of movement of the ribbon vibrator.

9. In a typewriting machine, the combination of a ribbon vibrator, a universal bar, and intermediate connections between said universal bar and vibrator, said connections including a pivoted member, and a device 110 adjustable relatively to said pivoted member and to either side of the pivotal center thereof.

10. In a typewriting machine, the combination of a ribbon vibrator, a universal bar, and intermediate connections between said universal bar and vibrator, said connections including a pivoted member actuated at each 115 printing movement, a member connectible at will with said pivoted member at either side of its pivotal center, and key actuated means for so connecting said members.

11. In a typewriting machine, the combination of a ribbon vibrator, a universal bar,

a rocking frame operatively connected with said universal bar, a connecting link between said rocking frame and the vibrator, and means for adjusting said link relatively 5 to said frame so as to change the direction of movement of the link and vibrator.

12. In a typewriting machine, the combination of a ribbon vibrator, a universal bar, a pivoted rocking frame operatively connected with said universal bar, a connecting link between said rocking frame and the vibrator, and means for adjusting said link relatively to said frame and to either side of the pivotal center thereof.

13. In a typewriting machine, the combination of a ribbon normally away from the printing point, and means for automatically moving the ribbon at each printing operation, said moving means including relatively adjustable members one change in the relation of which varies the extent of throw of the vibrator and another change in the relation of which changes the direction of movement of the vibrator from the normal position.

14. In a typewriting machine, the combination of a ribbon vibrator, and means for automatically actuating said vibrator at each printing operation, said means comprising a pivoted member, and a connecting member adjustable relatively to said pivoted member, an adjustment of said connecting member to different distances from the pivotal center of said pivoted member changing the throw of the vibrator and the shifting of the connecting member to opposite sides of the pivotal center of the pivoted member changing the direction of movement of the vibrator from the normal position.

15. In a typewriting machine, means for automatically moving a ribbon at each printing operation, said means including relatively adjustable parts adjustable at the will of the operator to provide varying extents of movement of the ribbon to bring different fields of the ribbon into operation or to provide a movement of the ribbon away from the printing point instead of to it at each operation, for the production of mimeograph sheets.

16. In a typewriting machine, means for automatically moving a ribbon at each printing operation, said means including relatively adjustable parts adjustable at the will of the operator to provide varying extents of movement of the ribbon from a fixed normal position to bring different fields of the ribbon into operation or to provide a movement of the ribbon from said fixed normal position away from the printing point instead of to it at each operation, for the production of mimeograph sheets.

17. In a typewriting machine, the combination of a ribbon vibrator, a universal bar, connections between said universal bar and

vibrator, said connections comprising a pivoted member, a connecting member, means for adjusting said connecting member different distances from the pivotal center of said pivoted member to change the throw of the vibrator in order to bring any one of a plurality of fields of the ribbon into operation and also for adjusting the connecting member to opposite sides of the pivoted member in order to change the direction of movement of the vibrator so that the ribbon may when desired be moved from its normal position away from the printing point and not be presented in the path of the types.

18. In a typewriting machine, the combination of a ribbon vibrator, a universal bar, intermediate connections between said universal bar and vibrator, said connections comprising a pivoted frame, an arm carried by said frame and extending transversely of and to opposite sides of the pivotal axis of said frame, and a connecting member adjustable along said arm and to opposite sides of the pivotal center of said frame.

19. In a typewriting machine, the combination of a ribbon vibrator, a universal bar, intermediate connections between said universal bar and vibrator, said connections comprising a pivoted frame, an arm carried by said frame and extending transversely of and to opposite sides of the pivotal axis of said frame, and a connecting link adjustably connected at one end to said arm, and key actuated means connected to said link for adjusting it along said arm and to opposite sides of the pivotal center of said frame.

20. In a typewriting machine, the combination of printing instrumentalities, finger keys therefor, a universal bar actuated at each depression of any one of said finger keys, there being a lost motion connection between said keys and said universal bar, a ribbon normally away from the printing point, and intermediate connections between said ribbon and universal bar, said connections including means adjustable at will for changing the direction of movement of the ribbon from the normal position by the universal bar.

21. In a typewriting machine, the combination of printing instrumentalities, finger keys therefor, a universal bar actuated at each depression of any one of said finger keys, there being a lost motion connection between said keys and said universal bar, a ribbon normally away from the printing point, and intermediate connections between said ribbon and universal bar, said connections including means adjustable at will for changing the extent and direction of movement of the ribbon by the universal bar, whereby any desired field of the ribbon may be rendered operative or the ribbon may be moved away from instead of towards the

printing point at each depression of a finger key.

22. In a typewriting machine, the combination of keys, a ribbon guide, and means for moving said ribbon guide away from the printing point at each down stroke of a key.

Signed at Syracuse, in the county of Onon-

daga, and State of New York, this 2nd day of February A. D. 1907.

CHARLES E. TOMLINSON.
